[57] CLAIM

The ornamental design for a hat keeper, as shown and described.

DESCRIPTION

FIG. 1 is a perspective view of a hat keeper showing my new design seen in relaxed position as it would appear lying on a surface, and including the connection string, slip fitting and circular end pieces;

FIG. 2 is a front view;

FIG. 3 is a right side view;

FIG. 4 is a left side view;

FIG. 5 is a rear view;

FIG. 6 is a top end view;

FIG. 7 is a bottom end view;

FIG. 8 is a front elevational view of a second embodiment of a hat keeper showing my new design, the end piece is shown separate for purposes of illustration, the opposite side is a mirror image;

FIG. 9 is a top view of the second embodiment;

FIG. 10 is a bottom view of the second embodiment;

FIG. 11 is a right side view of the second embodiment, the left side being a mirror image thereof;

FIG. 12 is a front elevational view of a third embodiment of a hat keeper showing my new design, the end piece is shown separate for purposes of illustration, the opposite side is a mirror image;

FIG. 13 is a top view of the third embodiment;

FIG. 14 is a bottom view of the third embodiment;

FIG. 15 is a right side view of the third embodiment, the left side being a mirror image thereof; and,

FIG. 16 is a side perspective view of the first embodiment of the hat keeper, the broken lines showing of the human form and hat is for illustrative purposes only and forms no part of the claimed design.
